UNITED STATES PATENT OFFICE.

JOHN HAYS HAMMOND, JR., OF GLOUCESTER, MASSACHUSETTS.

ELECTRICAL ANTENNA.

Application filed May 10, 1918, Serial No. 233,763. Renewed November 10, 1922. Serial No. 600,185.

To all whom it may concern:

Be it known that I, JOHN HAYS HAMMOND, Jr., a citizen of the United States, and a resident of Gloucester, in the county 5 of Essex and State of Massachusetts, have invented certain new and useful Improvements in Electrical Antennæ, of which the following is a specification.

Some of the objects of the present invention are to provide an antenna for use with 10 submerged dirigible bodies which is substantially invisible at a distance; to provide an antenna adapted to float upon and travel over the surface of a body of water and to receive and direct impulses of radiant energy to a receiving apparatus upon a submerged body; to provide an antenna which 15 presents a relatively small target area upon the surface of a body of water; to provide a light, flexible, buoyant antenna adapted to serve as a floating trailer for a submerged dirigible body; and to provide other improvements as will hereinafter appear.

In the accompanying drawings, Figure 1 20 represents a side elevation of a torpedo equipped with an antenna tube embodying the present invention; Fig. 2 represents a longitudinal section of the antenna tube; Fig. 3 represents a section on the line 3—3 25 of Fig. 2; Fig. 4 represents a longitudinal section of a portion of an antenna tube embodying a modified form of the invention; and Fig. 5 represents a section on the line 5—5 of Fig. 4.

Referring to the drawings, one embodiment of this invention comprises any suitable dirigible body adapted to be propelled beneath the surface of a body of water, for example a torpedo 10, which will be understood to be equipped with suitable wireless 35 receiving apparatus for electro-radiant energy and direction controlling mechanism operated by said apparatus.

For receiving the impulses of radiant energy to control the movement of the torpedo at will from a distance an antenna conducting strand 11 is provided consisting of a conducting strand of considerable length connected at one end to the wireless receiving set within the torpedo and having its outer end free but supported an appreciable distance above the surface of the water.

For supporting and properly positioning the conducting strand 11 above the surface 50 of the water the torpedo 10 is provided with a rigid tubular member 12 extending up-

wardly from the body of the torpedo 10 and preferably having a laterally and rearwardly disposed neck 13 to which a coupling or annular clamp 14 fixedly secures a casing 15 by a leak-proof joint. This casing 15, in the preferred construction, is of rubber, though it may be of any suitable dielectric water-proof substance, in the form of an elongated tube having a closed outer end 60 16 whereby the interior of the casing 15 is hermetically sealed and the contents thereof highly insulated from the surrounding body of water. The length of the member 12 is designed with respect to the depth of submergence of the dirigible body which carries it and its normal length is such as to position the neck 13 just above the level of the water whereby the casing 15 extends rearwardly in the line of the neck 13 resting 65 and trailing upon the surface of the body of water.

In order to support the antenna strand 11 within the casing 15 and suitably spaced from the walls thereof there are provided a plurality of bulkheads 17 of insulating material through each of which the antenna strand 11 passes and is held against displacement. The circumferential edges of the heads 17 conform to the contour of the casing 15, which is preferably circular in transverse section, while the diameter of the respective heads 17 is of sufficient length to maintain the casing 15 properly distended and spaced from the antenna strand 11 70 75 80 85 throughout its length.

To further maintain the casing 15 distended and in the form of an elongated tube it is equipped with a number of sleeves 20 of insulating material which are respectively inserted between the pairs of insulating heads 17 thus forming a plurality of chambers 21 which are filled with air to give the required buoyancy to the device so that it floats readily upon the surface of the water and maintains the antenna conducting strand 11 appreciably above the water level. The complete antenna therefor is an extremely light, buoyant structure, water-proof and air-tight, adapted to rest lightly upon the surface of the water and maintain the conducting strand 11 above the water level and insulated from the enveloping casing.

Where the conducting strand 11 enters the neck 13 it is supported by one of the heads 17 to prevent contact with the walls of the

member 12 and in order to further maintain this strand 11 spaced from the member 12 it is guided by suitable insulating discs 22 and in consequence reaches the interior of 5 the torpedo without contacting with any metal parts.

Another form of the supporting means for the conducting strand 11 is shown in Figs. 4 and 5 wherein the head construction 10 is dispensed with and a plurality of transversely and radially arranged wires 23 are substituted and which pass respectively through apertures 24 in the sleeves 20 and join rings 25 respectively through which the 15 strand 11 is adapted to pass and be suspended. The rings 25 are located along the longitudinal axis of the casing 15 in order to space the strand 11 equidistant from the interior walls of the several sleeves 20. In 20 this embodiment of the invention the juxtaposed ends of the pairs of sleeves 20 are spaced apart and the encasing tube for the strand 11 thus becomes a single long air-filled chamber of the desired flexibility and 25 buoyancy.

The floating antenna thus provided is comparatively long, for example, fifty feet, while in diameter it is relatively small, preferably about four inches, and consequently 30 when resting upon the surface of the water or being trailed thereover it is practically invisible and even if seen it presents a small target area, which is of paramount importance in this type of device. Furthermore 35 the extended form of conducting strand substantially paralleling the level of the water and above its surface has the advantage of being very directive along its length and extremely selective against the effects of 40 high potential stations in the vicinity, which are endeavoring to interfere. This is not merely on account of the directive effects which characterize this type of antenna, but is also thought to be due to the relatively 45 large capacity which does not allow a sudden building up of potential due to the high potential discharges of an interfering station. The large capacity is thought to be due in part to the parallel arrangement and 50 close proximity of the antenna with respect to the surface of the body of water, which acts as a condenser plate of considerable area. The same effect has been noticed in 55 antennæ when a large lump inductance has been added, the capacity in the present construction acting somewhat similarly. Thus while very sensitive receiving devices are necessary to receive on low antenna of this type, nevertheless the special attribute of 60 the antenna itself prohibits interference from affecting the receiving device.

Although only a few of the many forms in which this invention may be embodied have been described herein, it is to be understood that the invention is not limited to 65

any specific construction, but might be embodied in various forms without departing from the spirit of the invention or the scope of the appended claims.

What I claim is:

1. In a wireless apparatus, the combination of a submerged dirigible body, an antenna connected thereto comprising a conducting strand, a casing enclosing said strand consisting of an elongated buoyant tube hermetically sealed and adapted to float on the surface of a body of water, and means to insulate said conducting strand from said body of water. 70

2. In a wireless apparatus, the combination of a submerged dirigible body, an antenna connected thereto comprising a conducting strand, a hermetically sealed casing enclosing said strand, means including a plurality of sleeves to insulate and support said strand out of contact with the walls of said casing, and buoyant means to support said casing upon the surface of a body of water. 80

3. In a wireless apparatus, the combination of a submerged dirigible body, an antenna connected thereto comprising a conducting strand, a hermetically sealed casing enclosing said strand, and means to insulate and support said strand out of contact with the walls of said casing, said casing having a compartment filled with air to float said antenna on the surface of a body of water. 90

4. In a wireless apparatus, a buoyant antenna comprising an elongated flexible tube of insulating material, a plurality of heads spaced at intervals within said tube and cooperating with the walls of said tube to form air chambers and a conducting strand supported by said heads out of contact with said tube and terminating at one end within said casing. 100

5. The combination of an antenna and yielding buoyant means including a single, continuous flexible casing to support said antenna in close proximity to and substantially parallel with the surface of a body of water whereby said antenna flexes and conforms to the contour of the surface of the water under all conditions. 110

6. In a wireless apparatus, the combination of a torpedo, an antenna comprising an elongated, buoyant tube and a conducting strand sealed in said tube, and means connecting one end of said antenna to said torpedo, said means being arranged to cause said antenna to trail on the surface of the water at the normal submergence depth of said torpedo. 120

7. In a system for the transmission of intelligence by radiant energy, the combination with a dirigible body adapted to float in a medium, of means for intercepting radiant energy comprising a conducting strand, a hermetically sealed casing enclos- 125

ing said strand and spaced apart therefrom, buoyant means coextensive with said antenna to float said casing in a substantially horizontal plane, and means to insulate said 5 conducting strand from said body of water.

8. In a system for the transmission of intelligence by radiant energy, the combination with a dirigible body adapted to float in a medium, of means for intercepting 10 radiant energy comprising a conducting strand, a hermetically sealed casing enclosing said strand and spaced apart therefrom, buoyant means coextensive with said antenna extending substantially the full length 15 of the casing, and means to insulate said conducting strand from said body of water.

9. In a system for the transmission of intelligence by radiant energy, the combination with a dirigible body adapted to float 20 in a medium, of means for intercepting radiant energy comprising a conducting

strand, a hermetically sealed casing enclosing said strand and spaced apart therefrom, buoyant means coextensive with said antenna for sustaining substantially the full 25 length of the casing, and means to insulate said conducting strand from said body of water.

10. In a system for the transmission of intelligence by radiant energy, the combination with a dirigible body adapted to float in a medium, of means for intercepting 30 radiant energy comprising a conducting strand, a hermetically sealed casing enclosing said strand, and buoyant means at 35 spaced points in said casing for sustaining the casing in said medium.

Signed at New York in the county of New York and State of New York this 25th day of April A. D. 1918.

JOHN HAYS HAMMOND, JR.
